UNITED STATES PATENT OFFICE

GEORGEBEYS PAULOS PAPADOPoulos, OF DETROIT, MICHIGAN, ASSIGNOR OF SIXTY-SIX AND TWO-THIRDS PER CENT TO A. VICTOR BIZER, OF DETROIT, MICHIGAN

HAT BLOCK

Application filed November 12, 1931. Serial No. 574,629.

The present invention relates to new and useful improvements in hat blocks and has for its primary object to provide, in a manner as hereinafter set forth, a device of this character embodying a novel construction, combination and arrangement of parts through the medium of which the device may be expanded or contracted simultaneously in four directions.

10 Other objects of the invention are to provide a hat block of the aforementioned character which will be simple in construction, strong, durable, efficient and reliable in operation and which may be manufactured at low 15 cost.

All of the foregoing and still further objects and advantages of the invention will become apparent from a study of the following specification, taken in connection with 20 the accompanying drawings wherein like characters of reference designate corresponding parts throughout the several views, and wherein:—

Figure 1 is a plan view showing a hat block 25 constructed in accordance with the present invention with the sections in retracted position.

Figure 2 is a plan view of the hat block showing the sections extended.

30 Figure 3 is a detail view in cross section taken substantially on the line 3—3 of Figure 1 but with the sections extended.

Figure 4 is a sectional view taken substantially on the line 4—4 of Figure 1.

35 Figure 5 is a detail view in perspective of one of the end sections.

Figure 6 is a detail view in perspective of one of the side sections.

Figure 7 is a detail view in elevation of the 40 securing means for the metallic guides.

Referring to the drawings in detail, it will be seen that the hat block constituting the present invention comprises a substantially elliptical frame which is designated generally 45 by the reference numeral 1, said frame including the curved duplicate end sections 2 and the curved side sections 3 which are also duplicate. The end and side sections are adapted for end abutting engagement with each other 50 when said sections are in retracted position.

The end portions of the sections 2 are provided, on their upper and lower sides, with the recesses 4 for slidably receiving the guides 5 which are formed integrally with the metallic plates 6 which are rigidly secured to the 55 upper and lower sides of the sections 3 by securing elements comprising the headed, threaded connected male and female elements 7 and 8, respectively, which are illustrated in detail in Figure 7 of the drawings. 60 The guides 5 extend at an angle from the metallic plates 6 and are aligned with the end portions of the sections 2. The end portions of the sections 2 are provided with the slots 9 which terminate in spaced relation to the 65 ends of said sections 2, as best seen in Figure 5 of the drawings. Operable in the slots 9 are the pins 10 which extend between the pairs of guides 5. Sleeves 11 are rotatably mounted on the pins 10 for travel in the slots 9. 70

Extending from the slots 9 to the ends of the sections 2 are the grooves 12 in the upper and lower sides of said sections 2. The grooves 12 are aligned with the grooves 13 in the upper and lower sides of the sections 3. 75 At their inner ends the grooves 13 merge with the sockets 14 in the sections 3. The aligned grooves 12 and 13 are for the reception of the guide rods 15 having lateral heads 16 on one end engaged in the sockets 14 for anchoring 80 said guide rods in the sections 3. The sections 2 are slidable between the end portions of the guide rods 15 which project beyond the ends of the sections 3. It may be well to here state that the metallic plates 6 are 85 countersunk in the upper and lower sides of the sections 3, said sections 3 being recessed, as at 17, to accommodate the plates. The guide rods 15 extend adjacent the guide arms 5 and the metallic plates 6 provide means 90 for securing said guide rods 15 in position.

The opposed faces of the side sections 3 are provided with sockets 18 for the reception of the outer end portions of the oppositely threaded screws 19 which are anchored in 95 said side sections by the pins 20. A turn-buckle 21 in the form of a handle is operatively connected with the oppositely threaded screws 19 for simultaneously moving said screws outwardly or inwardly. 100

In use, when the side sections 3 are caused to move away from or toward each other by rotation of the turnbuckle 21, the end sections 2 are also caused to move simultaneously toward or away from each other through the medium of the pins and sleeves 10 and 11 which are carried on the guide arms 5 and which travel in the slots 9. The guide rods 15 prevent wobbling of the sections relative to each other and cause the ends of said sections to be brought squarely together when the sections are moved to fully retracted position.

It is believed that the many advantages of a hat block constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A hat block comprising a pair of side sections and a pair of end sections, said end sections having slots therein, means operatively connected with the side sections for shifting said side sections in opposite directions simultaneously, guide arms mounted on the side sections and extending slidably over the end sections, and pins mounted on the guide arms and extending through the slots for shifting the end sections in opposite directions relative to each other upon actuation of the side sections.

2. A hat block comprising a pair of side sections, means operatively connected with the side sections for shifting said side sections in opposite directions simultaneously, plates secured on opposite sides of the side sections, guide arms formed integral with the ends of the plates and extending therefrom at an angle, end sections mounted slidably between the guide arms, said end sections having slots therein, and pins mounted on the guide arms and operable in the slots for shifting the end sections in opposite directions simultaneously upon actuation of the side sections.

3. A hat block comprising side sections and end sections adapted for end to end abutting engagement, said sections having aligned grooves in their adjacent end portions, guide rods anchored in certain of the grooves and engaged slidably in the other grooves, means operatively connected with certain of the sections for shifting said certain sections in opposite directions simultaneously, and means connecting the other sections with said certain sections for actuation thereby in opposite directions relative to each other.

4. A hat block comprising side sections and end sections adapted for end to end abutting engagement, said sections having

aligned grooves in their adjacent end portions, guide rods anchored in certain of the grooves and engaged slidably in the other grooves, means operatively connected with certain of the sections for shifting said certain sections in opposite directions simultaneously, and means connecting the other sections with said certain sections for actuation thereby in opposite directions relative to each other, the last named means including pairs of guide arms mounted on said certain sections and projecting therefrom and slidably embracing said other sections therebetween, said other sections having slots therein, and pins extending between the pairs of guide arms and operable in the slots.

In testimony whereof I affix my signature.

GEORGE BEY PAULOS PAPADOPOULOS.
